UNITED STATES PATENT OFFICE

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA

FULL-FASHIONED-KNITTING MACHINE

Application filed November 9, 1928. Serial No. 318,183.

This invention relates to improvements in full fashioned knitting machines and more particularly it relates to an arrangement of needle bars and means for operating the 5 same.

An object of the invention is the provision of a support for two sets of needles, each set of needles to be independently adjustable on said support relative to the other knitting 10 implements.

Another object of the invention is to provide a support having thereon means for connection to oscillating means and also having thereon means for connection with lifting levers, the two said means being fixed in relation to each other.

Other objects will appear hereinafter.

The invention consists in the features, combination and arrangement of parts here- 20 inafter described and particularly pointed out in the claims.

Referring to the drawings:

Fig. 1 is an elevation of the yoke support and needle bars of my invention.

25 Fig. 2 is an end elevation of the device connected with oscillating means and lifting levers forming no part of the present invention and therefore shown in dotted lines.

In the drawings, 1 represents the yoke 30 shaped support with a depending portion 2 having means at its lower end comprising transverse bore 3 for pivotal connection with oscillating means 4.

The support 1 has laterally disposed oppo- 35 sitely extending arms 5 and 6 providing flat needle bar supporting surfaces 12 at the upper surface of the support. The arms 5 and 6 are each provided with a pair of angularly depending hinge ears 7 and 8 near their outer 40 ends. The pairs of hinge ears 7 and 8 are provided with transverse aligning bores 9, 9^a, 10 and 10^a, each pair being adapted to receive therebetween a lifting lever 11.

It is to be noted that the support carries 45 integral therewith the means for pivotal connection with the lifting levers and the means for pivotal connection with the oscillating means. In other words, the depending portion 2 is fixed in relation to the angularly 50 depending hinge ears 7 and 8, and these parts

being integral parts of the support 1, their relation is fixed and may not be altered.

Mounted on the flat surfaces 12 of the support are two independent needle bars 13 and 14 in each of which a set of series of needles is 55 set.

The needle bars are mounted for adjustment in a direction across the upper surface of the support to move the needles and adjust their position relative to the knitting implements. This invention provides the two needle bars on the support, each needle bar being entirely independent of the other, so far as adjustment of the bars on the support is concerned. 60

The support 1, carrying integral therewith the hinge ears and the depending member 2, is provided with vertical bores 15 of slightly larger diameter than clamping screws 16 to be received therein. The difference in the diameter of the bore 15 and the screw 16 determines the extent of the adjustability of the bars relative to the support. 65

Lugs 17 are provided on the support opposite the bores 15, the lugs extending above the upper surfaces 12 on the side of the support opposite to the needle, and the lugs being horizontally bored and threaded to receive adjusting screws 18, having lock nuts 19. The adjusting screws are adapted to engage, 70 adjust, and control the position of the bars on the support and hence the position of the needles relative to the other knitting elements.

Vertical screw threaded bores 20 in the bars align with the bores 15 in the support and receive the clamping screws 16, the heads of which clamp against the lower face of the support 1. 75

In the operation of the device, the needle bars may be adjusted on the support independently of each other, by loosening the clamp screws 16, so that horizontal movement of the bars on the support may be effected by operating the adjusting screws 18. 80

It is to be noted that adjustment of the bars does not entail any change in the relative position of the hinge ears and the support or its depending lever member 2, since these parts are integral. Change in the posi- 85 100

tion of the hinge ears relative to the depending member 2 would cause undue tipping of the needles which is undesirable, and which the present invention is designed to overcome.

Heretofore the two heads or sets of needles were mounted in a single bar, the depending operating lever for connection to the oscillating means being attached to the bar centrally thereof and the hinges being separately attached to the bar at or near its ends. With such construction, difficulty is encountered in keeping the needles in line, as the long bars will twist or warp, often rendering it necessary to take the bars out of the machine and peen them with a hammer or bend them back again to make them straight. Also, with such construction, in adjusting the needles in and out relative to the knitting implements, the angular position of the needles would be changed, due to the fact that in adjusting the needle bar relative to the hinge ears, the relation between the hinge ears and the depending lever member separately attached to the needle bar, is changed and the angular position of the needles is thus altered, which is undesirable. In other words, with the known construction, the adjustment moves the needle bar and depending lever member as a unit relative to the hinge ears which results in an objectionable change in the angular disposition of the needles.

With the structure of the present invention in which the depending lever member and hinge ears are integral, the two separate and independently adjustable shorter needle bars do not tend to twist or become otherwise distorted but are very easily kept in line, and the needle may be slid in or out without changing the angle.

It is apparent that modifications may be made within the scope of this invention and it is not desired to limit the invention to the exact structure shown.

I claim:

1. In combination in a full fashioned knitting machine, a support for the needles with means for reciprocating said support vertically and for moving the same forwardly and backwardly, and a pair of needle clamping bars on said support, said support having a pair of spaced apart openings for each needle bar, the members of each pair of openings being located near the ends of the bar to which they belong, and clamping bolts passing through the openings, said openings being larger in diameter than the diameter of the bolts to permit movement of adjustment of the bolts in all directions radially in respect to the axis of the openings, and means at each end of each bar for adjusting said bar, whereupon the clamping bolts may be set to hold the bar in its adjusted position, said clamping bolts forming the sole means of connecting

the needle bar with its support and permitting adjustment of the bar bodily to or from the knitting plane, or pivoted movement in respect thereto or lengthwise adjustment.

2. In combination in a full fashioned knitting machine, a support with means for moving it vertically and back and forth, two needle carrying bars arranged end to end, clamps connecting each of said needle carrying bars to the support, said clamps being spaced apart lengthwise of the needle carrying bar, each clamp having adjustment in all directions horizontally to permit each needle carrying bar to be bodily adjusted in any direction horizontally including an endwise adjustment, and means at or near each end of each needle carrying bar for adjusting said bar, said clamps when set holding the needle carrying bar to which they belong in fixed relation to the support, substantially as described.

In testimony whereof, I affix my signature.
KENNETH HOWIE.
